UNITED STATES PATENT OFFICE.

RAYMOND B. GLIDDEN, OF KEWANEE, ILLINOIS, ASSIGNOR TO KEWANEE IMPLEMENT COMPANY, OF KEWANEE, ILLINOIS, A CORPORATION OF ILLINOIS.

STOCK-WATERER.

1,387,483.

Specification of Letters Patent. Patented Aug. 16, 1921.

Application filed April 19, 1919. Serial No. 291,304.

To all whom it may concern:

Be it known that I, RAYMOND B. GLIDDEN, a citizen of the United States, and residing at Kewanee, in the county of Henry and State of Illinois, have invented certain new and useful Improvements in Stock-Waterers, of which the following is a specification.

The present invention aims to improve the construction of stock or hog waterers, and more especially those of the type in which the water may be heated. The general purpose of the invention is the provision of an appliance of this generic style which is of such structure that it can be manufactured at relatively small cost, that its parts may be readily separated, and that the heat applied to the water supply may be easily and comparatively uniformly distributed to it and also transmitted to the water in the trough. An added purpose of the invention is the production of such a waterer which shall be of relatively large capacity and which at the same time will not stand unduly high. Accordingly, the cylindrical water-supply tank is disposed horizontally in the preferred embodiment of the invention, fitted in a suitable frame, and has a trough at one end, the whole being incased in a suitable housing.

To enable those skilled in this art to understand the features of structure of an appliance embodying this invention I have illustrated in the accompanying drawing, forming a part of this specification, and throughout the various views of which like reference characters refer to the same parts, a preferred and desirable embodiment of the invention merely by way of example and not in a limiting or restricting sense with respect to the scope of the invention.

In this drawing:

Figure 1 is a central, longitudinal, vertical section through the appliance;

Fig. 2 is an end elevation of the same;

Fig. 3 is a vertical cross-section through the apparatus; and

Fig. 4 is a fragmentary, horizontal section through the trough portion of the structure.

Referring to the various views of the drawing, it will be understood that the improved and novel structure comprises a supporting, skeleton framework comprising four, upright, corner, angle-bar posts 10, 10 connected together at their lower ends

lengthwise the appliance by angle-bars 11, 11 and crosswise the structure by angle-bars 12, 12. As is clearly illustrated such posts or standards are braced by members 13 riveted thereto and to the upstanding flanges 60 of angle-bars 11 and 12. At their top ends such vertical posts are connected together longitudinally of the device by opposed angle-bars 14, 14 having horizontally-disposed inwardly-extended flanges 15. Transversely of the frame the posts are connected together by horizontal, flat, end bars 17. A rectangular sheet-metal pan 18 fits in the lower part of the frame resting on the horizontal flanges of the lower angle-bars. 70

Removably mounted in the rectangular top opening of such frame and supported by the inwardly-projecting flanges 15 of the longitudinal bars 14, 14 is a cylindrical, sheet-metal water-supply or reservoir tank 75 19 equipped at its top with an air-vent cock 20 and provided internally with an upright filling tube 21 extended downwardly from its top wall, through which it is open, to nearly the bottom of the tank. At one end 80 this tank has a head or round end-wall 22, and at its opposite end it has a similar head 23 provided with a rectangular aperture 24. The metal at the bottom margin or border of such opening, and forming an integral 85 part of the head, is bent outwardly at 25 and then downwardly at 26 parallel to the head.

In the tank, just back of such opening, is a trough member comprising a side-wall 90 sheet-metal element 30 semi-circular in horizontal section, the vertical edge portions of which extend out through the opening of the head at its corresponding margins and are then bent over at 31, 31 in opposite directions parallel to the head against which they bear and to which they may be secured as by soldering or otherwise. It will be noted that such semi-circular or curved member extends down below the lower border of 100 the head aperture and such section of the member is not provided with the flanges but its edges are soldered direct to the inner surface of the head or end-wall. This trough member has a half-round, horizontal, top-wall 32 which projects or extends forwardly through the opening 24 and the front of the head is bent up to provide a flange 33 which is soldered to the outer face of the head. Such trough member at its bottom is 105 110

equipped with a similar half-round floor or wall 34 soldered around its border or edge to such member and to the back of the tank head.

5 Slightly below the height of flange or lip 25 to prevent overflowing, the wall 30 has a hole or aperture 35 establishing communication between the interior of said tank and the trough, to the latter of which the animal 10 has access through the window or aperture 24. Thus the trough is automatically replenished or kept filled with water to the established or predetermined level from the supply in the storage or reservoir tank.

15 Such combined tank and trough and its supporting frame are adapted to be incased in a sheet-metal housing or shell 40 having a semi-cylindrical upper part and a rectangular, lower section, thus being shaped in a 20 general way to the form of the appliance it is intended to house. Near the bottom at one side such casing has a vertically sliding door 41 permitting access to a lamp or stove 42 resting in the pan 18. At one end such 25 casing has an opening 43 in register with the trough aperture 24 of the supply tank and the sheet-metal along the opposite vertical margins and across the top border of the opening is bent inwardly at 44 and 45 30 and projects slightly through the opening of the tank. When the housing and tank are associated together the sheet-metal of the former along the lower margin of its opening is covered by the outstanding lip 35 40 and is received between the corresponding bar 17 of the frame and the downturned flange 26. Thus, a neat finish is secured around the opening 43 and the heated air of the housing is prevented from escaping 45 around the trough, it being understood that there is adequate space between the casing and tank at all points to permit efficient heating of the tank and trough and their contents by the circulation of the heated air.

45 It may be noted that the stem or connection of the air-vent cock or valve 20 is located outside of the outer casing or housing and is hence readily accessible for manipulation or operation, the top curved wall of 50 the housing being cut away to permit the extension of the stem or pipe connection therethrough.

The appliance is also equipped or supplied with a removable funnel 50 having a spout 55 51 projecting down through a hole 52 in the casing and into the filling pipe or tube 21. Thus this funnel and its neck by closing the aperture 52 prevent the escape of the heated air from the casing.

60 The method of operation and refilling such appliances and the principles employed are so well known that they do not require explanation, but it is to be observed, that the water-supply tank is horizontally disposed, 65 hence giving the apparatus a desirable low

center of gravity, that the trough is inside of the tank at one end, its contents thus being subject to the transfer of heat thereto from the water of the tank, and that the semi-circular wall of the trough is not only well adapted to withstand the water pressure in the tank exerted against it but its curved surface also facilitates the flow of heated water currents around the trough thus aiding in keeping the contents of the latter, although exposed to the outer cold air, sufficiently warm to prevent freezing even in the coldest weather.

70 When required the outer casing may be readily removed or lifted off by first bending the flanges 44 and 45 to permit such separation of the parts, whereupon the casing may be easily released from the hook-shaped flange 25 and 26, permitting it to be elevated 75 away from the tank and its supporting framework.

80 This invention is not limited and restricted to any particular embodiment since it is susceptible of being incorporated in appliances of radially different physical characteristics and accordingly many minor changes may be made in the structure presented without departure from the fundamental principles underlying the invention 85 and still fall within the scope and breadth 90 of the appended claims.

95 I claim:

1. In a stock watering-appliance of the character described, the combination of a cylindrical water-supply tank, means to support said tank with its axis substantially horizontal, a head of said tank having an opening, and a trough inside of said tank and in communication with the water-supply thereof to which trough the animal has 100 access through said opening, said trough having a substantially semi-circular apertured side-wall, the edge portions of which extend through said head opening and are bent over to form flanges outside of and secured to the head, a bottom wall above the bottom of the tank, and a top wall having an edge portion extended through said head opening and bent over to form a flange outside of and secured to said head, 110 substantially as described.

115 2. In a stock-watering appliance of the character described, the combination of a skeleton frame having a top opening, a cylindrical water-supply tank supported with its axis substantially-horizontal by resting on the longitudinal bars of the frame bordering said top opening with the lower part of the tank projecting downwardly into said frame opening, said tank being unattached to said frame, a head of said tank having an opening, and a trough inside of said tank and in communication with the water-supply thereof to which trough the animal has access through said head open- 125 130

ing, the front wall of said trough being formed by said tank head, said tank head also having an outwardly extended lip at the bottom margin of said head opening 5 overlying a cross-bar of said frame, substantially as described.

3. In a stock-watering appliance of the character described, the combination of a skeleton frame having a top opening, a 10 cylindrical water-supply tank supported with its axis substantially-horizontal by its curved cylindrical wall resting on the longitudinal bars of the frame bordering said top opening with the lower part of the tank 15 projecting downwardly into said opening, said tank being unattached to said frame, a head of said tank having an aperture, a trough inside said tank and in communication with the water-supply thereof, to 20 which trough the animal has access through said head aperture, a casing housing said frame and tank and apertured in register with the aperture of said head, said combined tank and trough having a lip along 25 the lower margin of said head aperture projecting through and overlying the bottom margin of said casing aperture, substantially as described.

4. In a stock-watering appliance of the 30 character described, the combination of a skeleton frame having a top opening, a cylindrical water-supply tank supported with its axis substantially-horizontal by its curved cylindrical wall resting on the longitudinal bars of the frame bordering said top 35 opening with the lower part of the tank

projecting downwardly into said opening, said tank being unattached to said frame, a head of said tank having an aperture, a trough inside said tank and in communication with the water-supply thereof, to which trough the animal has access through said head aperture, a casing housing said frame and tank and apertured in register with the aperture of said head, said combined tank 40 and trough having a lip along the lower margin of said head aperture projecting through and overlying the bottom margin of said casing aperture and also overlying a cross bar of said frame, said lip having 45 a downturned flange overlapping the outer face of said casing, substantially as described.

5. In a stock-watering appliance of the character described, the combination of a 50 cylindrical water-supply tank, a frame supporting said tank with its axis substantially-horizontal, a head of said tank having an aperture, a trough inside said tank and in communication with the water-supply thereof, to which trough the animal has access through said head aperture, a casing housing said frame and tank and apertured in register with the aperture of said head, said combined tank and trough having a lip along 55 the lower margin of said head aperture projecting through and overlying the bottom margin of said casing aperture and overlying a cross-bar of said frame and having a downturned flange outside of said casing, 60 substantially as described.

RAYMOND B. GLIDDEN.
